UNITED STATES PATENT OFFICE.

ROBERT H. GIBBS AND BYRON W. THIELE, OF PORTLAND, OREGON.

SKIRT HANGER.

Application filed August 1, 1922. Serial No. 578,924.

To all whom it may concern:

Be it known that we, ROBERT H. GIBBS and BYRON W. THIELE, citizens of the United States, residing at Portland, in the county 5 of Multnomah and State of Oregon, have invented certain new and useful Improvements in Skirt Hangers, of which the following is a specification.

This invention relates to improvements in 10 garment hangers, designed primarily for hanging skirts, but it is to be understood that the device can be employed for any purposes wherein it is found applicable, and has for its object, to provide a device 15 of this class, in a manner as hereinafter set forth, for supporting or hanging skirts of different sizes and which will automatically and positively hold itself in any adjusted position.

20 Further objects of the invention are to provide a garment hanger, which is simple in its construction and arrangement, strong, compact, automatically adjusting itself to garments of various sizes, durable, convenient and efficient in its use, readily assembled and inexpensive to manufacture.

With the foregoing and other objects in view, the invention consists of the novel construction, combination and arrangement 30 of parts, as hereinafter more specifically described and illustrated in the accompanying drawings, wherein is shown an embodiment of the invention, but it is to be understood that changes, variations and modifications 35 can be resorted to which come within the scope of the claim hereunto appended.

In the drawings wherein like reference characters denote corresponding parts throughout the several views:—

40 Figure 1 is an elevation of a garment hanger in accordance with this invention and further illustrated in dotted lines, the supporting arm shifted to adjusted position,

45 Figure 2 is a sectional plan,

Figure 3 is a section on line 3—3, Figure 1,

Figure 4 is a section on line 4—4, Figure 1,

50 Figure 5 is a view similar to Figure 1 of a modified form and,

Figure 6 is a sectional plan of the modification.

Referring to Figures 1 to 4 of the drawings, 10 denotes a supporting member 55 formed of an elongated flat narrow strip of suitable material, preferably wood, and which is provided in proximity at each end thereof with a combined stop, guide and retaining element in the form of an inverted yoke, as at 11, and which has the arms thereof secured to the side faces of the member 10, by the hold-fast devices 12. Each of the elements 11 is positioned slightly inwardly with respect to an end of the member 10.

Mounted on the member 10 is a pair of oppositely disposed hanger arms 13, 14, and each of which is formed of an elongated flat, narrow strip of suitable material, preferably wood and of a width equal to the width of the member 10, so that the sides of the arms 13, 14 will be flush with the sides of the member 10. The arms 13, 14, are automatically adjustable laterally with 75 respect to the member 10 and the means for such adjustment of the arms 13, 14 will be presently referred to. The inner end of each of the arms 13, 14, is provided with a combined guide and retainer element, in the 80 form of a yoke, as at 15, and the arms of the yoke 15 are secured to the sides of a hanger arm by the hold-fast devices 16.

The combined stop, guide and retaining elements 11 overlap the hanger arms 13, 14, 85 whereby these latter are connected with the member 10 and are guided during the adjustment thereof. The combined guide and retaining elements 15 overlap the member 10 and connect the arms 13, 14, to said member 10 as well as to provide guides during 90 the adjustment of the hanger arms.

The outer end of each of the arms 13, 14, has secured thereto, by the hold-fast devices 17, a pad 18, which has a curved periphery, and is of a material different from that which the hanger arms are constructed of, and of a material as not to damage the article which is suspended from the hanger arm.

100 Each of the hanger arms 13, 14, in proximity to the element 15, has secured thereto at its longitudinal center a vertically disposed transversely extending eye 19, and to which is loosely connected the looped lower 105 end 20, of an arm of an expansible and con-

tractile bail 21, which is coiled intermediate its end, as at 22, to increase the tension thereof. The function of the bail 21 is to normally project the hanger arms 13, 5 and to further provide means whereby the hanger arms can be adjusted laterally, with respect to the member 10, when the device is employed to hang garments or skirts of different size. The outward movement of the 10 hanger arms 13, 14, is arrested through the medium of the elements 11, which are adapted to engage the eyes 19 on the outwardly movement of the arms 13, 14, whereby such movement is arrested.

15 Referring to Figures 5 and 6 of the drawings, the device is formed of a pair of hanger arms 23, 24, the former being of greater length than the latter and the latter is mounted and shifts on the arm 23. 20 The outer end of each of the arms 23, 24, has secured thereto, a pad 25 for the same purpose as the pad 18. The inner end of the arm 23 has secured thereto, by the holdfast devices 26, a combined stop, guide and 25 retaining element which consists of a vertically disposed inverted yoke 27 overlapping the arm 24, whereby the latter is connected to the arm 23. The inner end of the arm 24 has secured thereto, by the holdfast devices 28, a depending combined guide and retaining element 29, which overlaps the arm 23, whereby the latter and the arm 24 are connected together.

Secured to each of the arms 23, 24, intermediate the ends thereof, is an eye 30, to which is connected the looped lower end 31, of a leg of an expansible and contractible bail 32, which is coiled as at 33 to increase the tension thereof.

40 The element 27 acts as a stop to limit the outward movement of one of the legs of the bail 32 so that the arms 23, 24, cannot be separated. If the arm 23 is shifted laterally with respect to the arm 24, the element will 45 engage an eye 30 and if the arm 24 is shifted outwardly with respect to the arm 23, the

same eye referred to will engage the element 27.

The bails 21 and 32 normally project the hanger arms outwardly to the outward 50 limits of their movement and the hanger arms can be readily shifted inwardly, against the tension of the bails, so that the hanger can be adjusted to provide for suspending or hanging garments of different 55 size.

The coiled portion of each of the bails provides means to permit of the hanger being mounted on a supporting element.

What we claim is:—

60 A skirt hanger comprising a rectangular support, a pair of automatically adjustable and oppositely extending laterally movable rectangular hanger arms slidably mounted on the top of said support, a yoke-shaped 65 guide secured to the sides at the inner end of each of said arms and overlapping and slidably connecting said arms to said support, an inverted yoke-shaped combined stop and guide secured to the sides at each 70 end of said support and overlapping and slidably connecting said arms to the support, an expansible and contractile bail coiled centrally of its ends to provide a pair of resilient arms, each of said bail arms 75 having its free end formed with a loop, a vertically extending eye secured to the inner end of each of said hanger arms forwardly with respect to a guide and loosely connecting a looped end of a bail arm to a 80 hanger arm, said eyes disposed at the longitudinal center of and extending transversely with respect to said hanger arms and engageable by said combined guide and stop members to arrest the outward movement im- 85 parted to said hanger arms by said bail arms.

In testimony whereof we affix our signatures hereto.

ROBERT H. GIBBS.
BYRON W. THIELE.
